(57) **CLAIM**

The ornamental design for a storage device, as shown and described.

DESCRIPTION

FIG. 1 is a front right perspective view of a storage device in accordance with an embodiment of the claimed design; FIG. 2 is a front elevation view of the design of FIG. 1; FIG. 3 is a right side elevation view of the design of FIG. 1; FIG. 4 is a left side elevation view of the design of FIG. 1; FIG. 5 is a top plan view of the design of FIG. 1; FIG. 6 is a front right perspective view of a storage device in accordance with another embodiment of the claimed design;

FIG. 7 is a front elevation view of the design of FIG. 6; FIG. 8 is a right side elevation view of the design of FIG. 6; FIG. 9 is a left side elevation view of the design of FIG. 6; and,

FIG. 10 is a top plan view of the design of FIG. 6.

The rear elevation views and bottom plan views of each of the embodiments illustrated are not shown and form no part of the claimed design.

The dash-dash broken lines in the figures represent environment and form no part of the claimed design.

The dot-dash lines in the figures immediately adjacent the solid lines represent a symbolic break in length. The appearance of any portion of the article between the break lines forms no part of the claimed design. It is understood that the symbolic break lines represent boundaries of the claimed design and form no part thereof.
